UNITED STATES PATENT OFFICE.

TRACY V. BUCKWALTER, OF ALTOONA, PENNSYLVANIA.

RADIATOR.

1,256,977.

Specification of Letters Patent. Patented Feb. 19, 1918.

Application filed July 11, 1916. Serial No. 108,687.

To all whom it may concern:

Be it known that I, TRACY V. BUCKWALTER, a citizen of the United States, residing at Altoona, in the county of Blair and State of Pennsylvania, have invented an Improved Radiator, of which the following is a specification.

This invention is an improved radiator for cooling engines, especially of the internal combustion type, and it is designed primarily for cooling such engines on cars intended to be run in reverse directions, as in the case of section cars used on railroads, for example, but it will be understood that it is applicable to more general use.

My improvements are characterized by the combination, with a circulating system for the cooling fluid, of a centrifugal blower which draws air from opposite directions and forces it through the system.

The primary object of my invention is to provide a more efficient cooling system, which will operate efficiently at all times, whether the car is running forward, backward or standing still.

A further object of my invention is to prevent a draft, through the center of the cooling apparatus, that would interfere with the desired circulation of the air in contact with the surfaces to be cooled.

The nature and characteristic function of my invention will fully appear from the following description and the accompanying drawings in illustration thereof.

In the drawings, Figure 1 is a part sectional elevation of an embodiment of my invention; and Fig. 2 is a sectional view taken on the line 2—2 of Fig. 1.

The invention, in the form thereof illustrated in the drawings, comprises the supports 1 (which may be longitudinal sills of a car) having the radiator 2 mounted thereon, the radiator comprising a cooling fluid circulating system having a top header 3, a bottom header 4, and sets of tubes 5 with their respective ends connected by the headers 3 and 4.

Plates 2', containing apertures 2'', connect the headers 3 and 4 on opposite sides of the tubes 5, and form therewith a partially enclosed space for the tubes, the space having free central openings in the apertures 2'' between the sets of tubes and the free end openings 2''' at opposite sides thereof.

Open bearings or spiders 6 and 7, fixed to the plates 2', over the apertures 2'', on op-

posite sides of the structure, carry the shaft 8. A hub or hollow shaft 9 is journaled on the shaft 8 and has thereon a solid diaphragm or web 10 provided with conoidal sections 10' and 10'' fixed to the hub, vanes 11 being fixed on opposite sides of the periphery of the web and supporting rings 12 connecting the outer ends of the vanes. The vane wheel or fan, thus provided, is revolved by a sprocket wheel 14 which is fixed to the hub 9 and driven in a usual manner.

Baffles or chokers 15 are fixed to the respective headers 3 and 4, between the plates 2' and the sets of tubes 5, so that the free space around the vane wheel shall be restricted and the efficiency of the blower increased, the effect being to obtain a more active circulation of air in contact with the tubes.

As the revolution of the vane wheel draws air through the central apertures 2'' and forces it outwardly in opposite directions, between the plates 2' and the headers 3 and 4, through the spaces containing the tubes 5, the circulating system is actively cooled by a forced draft at all times, whether the apparatus is stationary or moving in either direction. As the web 10 of the vane wheel is disposed between the ports 2'' transversely to the direction of movement, which is in line 85 with the axis of the wheel, the direct passage of air between the ports is prevented and its active circulation in contact with the tubes is compelled without regard to the direction of movement of the apparatus, the pressure 90 of the air opposite to the direction of movement facilitating the cooling action by producing a draft through the forward aperture and outwardly over the tubes due to the deflecting action of the fan's web.

Having described my invention, I claim:

1. In a radiator, the combination with a structure comprising cooling fluid circulating means and having apertures for the passage of air for cooling said means, of a journaled fan adapted for circulating air in contact with said means and having a diaphragm adapted for preventing the direct passage of air between said apertures.

2. In a radiator, the combination with cooling fluid circulating means comprising a plurality of sets of tubes, of air circulating means comprising a journaled fan having vanes adapted for forcing air outwardly between said tubes and a diaphragm on opposite sides of which the vanes aforesaid are disposed.

3. In a radiator, the combination with cooling fluid circulating means comprising headers and sets of tubes having their ends connected by said headers, of a journaled fan between said sets of tubes and said headers, said fan having a diaphragm, and means providing air ports on opposite sides of said fan, said ports being separated and the passage of air between them being prevented by said diaphragm.
4. In a radiator, the combination with cooling fluid circulating means comprising headers and sets of tubes having their ends con-

nected by said headers, of plates connected with said headers and having oppositely disposed apertures, a journaled wheel having a web disposed between said apertures and vanes separated by said web, and chokers for restricting the free space around said wheel and for facilitating the active circulation of air by said wheel in contact with said tubes.

In testimony whereof I have hereunto set my name this 29th day of June, 1916.

TRACY V. BUCKWALTER.
